UNITED STATES PATENT OFFICE.

FRANK PHILIPPI, OF PHILADELPHIA, PENNSYLVANIA.

UTILITY CASE.

Application filed April 8, 1927. Serial No. 181,913.

My invention relates to utility cases and particularly to a case adapted to meet all the ordinary requirements of a traveler.

When traveling, a person often desires to have toilet articles and other accessories, articles of clothing and equipment, and means for writing conveniently associated so that any of the articles may be readily reached or letters written with a minimum of inconvenience, and the principal object of my invention is to provide a case that will allow the above requirements to be met.

Another object of my invention is to so design the case that it will be compact, neat in appearance and easily handled.

These objects, and other advantageous ends which will be described hereinafter, I attain in the following manner, reference being had to the accompanying drawings 20 in which—

Figure 1 is an end view of a case embodying my invention, and

Figure 2 a cross sectional view of the case shown in Figure 1.

Figure 3 is a plan view of the case in opened position,

Figure 4 a front view showing the case in opened position and with the accessory carrying members raised.

Figure 5 is a plan view showing the case opened, the desk tray extended and the accessory carrying members raised.

Figure 6 is a side view of the case as it is shown in Figure 5, and

Figure 7 is a sectional view, partly in full, taken on line 7—7 on Figure 5 with the upper part of the accessory carrying members broken away.

Referring now more in detail to the drawings, the case has a rectangular body part 10 to which a cover part 11 is attached by means of a hinge 12 and adapted to be secured in closed position by means of a lock 13 attached to body part 10. Body part 10 is provided with a handle 14 and has a slot 15 formed in its upper side adjacent its rear wall 16 in which is slidably mounted a desk tray 17 which may be drawn outwardly by means of a tab 18 secured to its outer edge.

Desk tray 17 is provided with suitable corner pieces 19, for the reception of a blotter as is customary in desk pads, and has a strip 20 rigidly secured to its rear or bottom edge and provided with parts of snap fasteners

21. An accessory carrying member 22 is provided with a hinged portion 23 in which the

other halves of snap fasteners are rigidly secured so it may be snapped onto strip 20. Another accessory carrying member 24 has one edge hinged to the other edge of accessory carrying member 22 and its other edge hinged to the bottom piece 25 of body part 10. Accessory carrying members 22 and 24 are provided with a plurality of suitable pockets or straps 26 adapted to receive toilet articles or other accessories and member 22 is preferably provided with a mirror 27.

By releasing lock 13 and swinging the case upon hinge 12, it may be laid flat and desk tray 17 pulled outwardly by grasping tab 18. 70 Desk tray 17 cannot be completely withdrawn from body part 10 as strip 20 will make contact with the inside of the top of the case. Members 22 and 24 are automatically drawn into raised position by drawing desk tray 17 outwardly as hinged portion 23 is secured to strip 20.

Desk tray 17 is slidably mounted between rear wall 16 and a pair of guides 28 secured to the ends of body part 10; guides 28 being adapted to hold the desk tray against tilting when it is extended. Hinged portion 23 and strip 20 are slidably fitted between guides 28 so as to hold members 22 and 24 in alignment when they are in raised position and guide them into the correct position when the case is closed.

Should it be desired to have the articles on both members 22 and 24 within easy reach, hinged portion 23 may be removed from strip 20 by separating snap fasteners 21 and extending portion 22 over the top of the case in the position occupied by desk tray 17 when it is in extended position.

Cover part 11 may be provided with a bellows portion 29, in order to provide a greater capacity for the case, or the rear wall 30 of bellows portion 29 may be firmly secured to cover part 11 as desired. Pockets 31 are formed of suitable material and attached to the inside of wall 30 and adapted to receive small articles of wearing apparel and equipment. Other articles may be packed in cover part 11 and held against movement by straps 32, as is customary in conventional types of baggage. Also, straps may be attached to cover part 11 and pass around the outside of bellows portion 29 in order to hold same against distending when its interior is not completely filled with material.

The parts 10 and 11 may be made of wood or binder's board, as is customary in manu-

facturing baggage, and may be covered with any suitable material, such as leather or an imitation thereof. Rear wall 30 is preferably made of binder's board and covered with the same material that the case proper is covered with while members 22 and 24 are preferably made of binder's board and covered with suitable fabric. In the drawings, it has been necessary to exaggerate the thicknesses of materials and of the case itself in order to properly illustrate the relative locations of the various parts.

With the case made in this manner, the user has available, for instant use, necessary articles of apparel and equipment, toilet articles, a mirror, and a writing desk. When the case is closed, the different parts are disposed in close proximity to one another so that there is practically no waste space; thus producing a case that is compact, light in weight and attractive in appearance.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the appended claims.

I claim:

1. A utility case including a body part, guides fixed in the body part, a desk tray slideable behind the guides and extendible from the body part, an accessory carrying member hinged to the body part, and a second accessory carrying member hinged to said member and to the desk tray, whereby extending the desk tray will cause the accessory carrying members to stand at an angle to the body part and retracting the desk tray will cause said members to fold together.

2. A utility case including a body part, guides fixed in the body part, a desk tray slideable behind the guides and extendible

from the body part, a strip fixed to the desk tray and slideable between the guides, an accessory carrying member hinged to the body part, and a second accessory carrying member hinged to said member and to the strip, whereby extending the desk tray will cause said members to stand at an angle to the body part and the guides will keep said members in alignment with the body part.

50

55

3. A utility case including a body part, a desk tray extendible therefrom, a securing part separably connected to the desk tray, guides fixed in the body part for holding the desk tray against lateral movement and the securing part against longitudinal movement, an accessory carrying member hinged to the body part, and a second accessory carrying member hinged to said member and to the securing part whereby extending the desk tray will cause said members to stand at an angle to the body part and the guides will keep them in alignment therewith.

60

65

4. In a utility case having a body part, a slot in the body part, and a desk tray extendible through the slot; an accessory carrying member hinged in the body part, a second accessory carrying member hinged to said member and to the desk tray, whereby extending the desk tray will cause said members to stand at an angle to the body part.

70

75

5. In a utility case having a body part, a slot in the body part, and a desk tray extendible through the slot; a securing part separably connected to the desk tray, an accessory carrying member hinged in the body part, a second accessory carrying member hinged to said member and to the securing part, whereby extending the desk tray will cause said members to stand at an angle to the body part, and whereby the securing part may be detached from the desk tray, and the accessory carrying members extended in substantially the same plane.

80

85

In testimony whereof I have signed my name to this specification.

FRANK PHILIPPI.
